CLAIM

The ornamental design for a LED hanging ring toss board, as shown and described.

DESCRIPTION

FIG. 1 is a perspective front view of the LED hanging ring toss board.

FIG. 2 is a front view of the LED hanging ring toss board.

FIG. 3 is a side view of the LED hanging ring toss board. The opposite side view is a mirror image.

FIG. 4 is a top view of the LED hanging ring toss board; and, FIG. 5 is a bottom view of the LED hanging ring toss board. The rear of the LED hanging ring toss board is flat and devoid of surface ornamentation.

A characteristic feature of the design resides in the light emitting diodes which emit light from the perimeter sides of the rectangular center portion of the hanging ring toss board. The broken lines illustrating the emitting lights around the inner circle form no part of the claimed design. The remaining broken lines depict portions of the LED hanging ring toss board that form no part of the claim.

1 Claim, 5 Drawing Sheets
